UNITED STATES PATENT OFFICE.

OTHMAR DE COURTEN AND OSCAR SCHAUB, OF BASEL, SWITZERLAND.

ADVERTISING ON CIGARETTES.

Application filed April 16, 1928, Serial No. 270,538, and in Switzerland April 27, 1927.

This invention relates to advertising on cigarettes and has for its principal object to provide a particularly effective advertisement on a cigarette which shall not however 5 inconvenience the smoker.

According to the invention the advertisement does not appear upon the body of the cigarette but is applied to a small flag or tab connected to or integral with the casing of the cigarette, a particularly effective advertisement being thus provided which does not inconvenience the smoker of the cigarette inasmuch as the small advertising flag or tab can be readily removed.

Figures 1 and 2 of the accompanying drawing illustrate by side views two embodiments of the invention.

In both cases, a small flag or tab *a* bearing an advertisement is connected to the body *b* 20 of the cigarette so as to extend laterally therefrom but could however be arranged so as to lie against the body of the cigarette.

The advertising flag or tab *a*, which is preferably made of the same material as the 25 casing of the cigarette may be of any desired shape as, for example, rectangular, triangular, round, oval, etc.; around its periphery it may be curved, scalloped, toothed or have any fantastic form and it may be of any desired colour. It may moreover be adapted 30 to be separated from the body of the cigarette and may for this purpose be perforated as illustrated at *c* in Figure 1 for example.

The flag or tab *a* may also be made in 35 one piece with the paper casing of the cigarette, as represented in Figure 2 of the draw-

ing, in which case provision is made for readily separating the flag or tab by perforating or stamping the latter along a line of separation indicated at *d*. 40

When the flag or tab is arranged to extend laterally from the body of the cigarette, the advertisement appearing thereon is exhibited to the greatest advantage and when it is adapted to be separated from the body of the 45 cigarette the advertisement is even more effective inasmuch as the smoker in separating the tab must necessarily become cognizant of the advertisement.

The tab or flag need not however extend 50 laterally from the body of the cigarette but could when the cigarette is being packed be rolled around the body of the cigarette and only be released when the latter is removed from the packet for use. 55

What we claim is:—

1. A cigarette having an advertisement carrying flag or tab made in one piece with the paper casing of the cigarette and arranged to be separated therefrom along a 60 "tearing-off" line.

2. A cigarette having an advertisement carrying flag or tab made in one piece with the paper casing of the cigarette and having a line of perforations for separating 65 purposes.

In witness whereof we have hereunto signed our names this fifth day of April, 1928.

OTHMAR DE COURTEN.
OSCAR SCHAUB.
